UNITED STATES PATENT OFFICE.

HARRY M. McCASLIN, OF ELMIRA, NEW YORK, ASSIGNOR TO AMERICAN LA FRANCE FIRE ENGINE CO., INC., OF ELMIRA, NEW YORK, A CORPORATION OF NEW YORK.

FIRE-EXTINGUISHER.

1,291,044.

Specification of Letters Patent.

Patented Jan. 14, 1919.

Application filed March 22, 1918. Serial No. 223,939.

To all whom it may concern:

Be it known that I, HARRY M. McCASLIN, a citizen of the United States, residing at Elmira, in the county of Chemung and State 5 of New York, have invented certain new and useful Improvements in Fire-Extinguishers, of which the following is a full and clear specification.

The present invention relates to improvements in fire extinguishers especially applicable to automobiles, railroad and marine use. The main object of the invention is to produce an extinguisher which will be less liable to slopping over than such extinguishers heretofore have been.

The present improvements relate especially to the tip over type of extinguisher in which the acid contained in a bottle is commingled with the carbonate of soda solution by turning the extinguisher upside down.

The first feature of novelty in the present invention consists in the novel form of acid bottle. The bottle is constructed with the 25 usual contracted neck at the top and with a second contraction or neck approximately half way between the top and bottom to form a bottle with two distinct chambers connected through the contracted passage way 30 of the central neck. The improved bottle is designed to have the acid fill the lower chamber up to the central contraction or neck, leaving the upper chamber entirely free to accommodate any accumulation of 35 moisture from the soda solution. The bottle has its mouth normally covered by a loosely fitting lead stopple operating in the usual way. With this construction of acid bottle there is a very small surface of the 40 acid exposed, so that the acid will be subjected to the minimum amount of disturbance when the extinguisher, as a whole, is shaken up.

The improved form of acid bottle is preferably employed in combination with the tip over type of extinguisher, in which it is preferred to employ an improved form of conical baffle supported from the mouth of the tank or container, around the acid bottle and 50 the discharge outlet is through an upwardly extending goose neck or elbow, which tends to drain back into the extinguisher any liquid that slops over, into the outlet, opening except when the extinguisher is inverted 55 for use.

In order that the invention may be fully

understood it will first be described with reference to the accompanying drawings and afterward pointed out more particularly in the annexed claims.

In said drawings,

Figure 1 is a vertical sectional view of the improved extinguisher;

Fig. 2 is an enlarged vertical sectional view of the improved acid bottle;

Figs. 3 and 4. are transverse sectional views, taken respectively upon the sectional lines 3-3 and 4-4 of Fig. 2.

1 is the usual fire extinguisher tank or container, formed with an open mouth 2 and 70 the flanged bottom 3, in which is mounted the usual hand hold 4.

The open mouth is normally closed by the removable screw-threaded top or cover 5.

10 is an acid bottle cage, formed of an 75 approved skeleton construction, with a flanged upper ring 11, fitting loosely in the open mouth of the container and resting upon a plurality of internal lugs, one of which is indicated at 12. This bottle cage 80 supports the acid bottle which will presently be explained. Depending from the cover 5, within the container are fingers 15, adapted to engage the upper shoulder of the acid bottle when the extinguisher is inverted 85 in the usual manner.

The acid bottle is formed with a lower portion 20, and an upper portion 21, connected by a contracted central neck 22, which divides the bottle into two chambers, communicating through the channel of the contracted neck. The usual open mouth neck 23 at the top of the bottle is normally closed by the lead stopple 25. The acid bottle rests in the cage 10, in the usual manner.

30 is a conical baffle plate supported at its contracted upper end within the mouth 2 of the tank or container and flaring outwardly and downwardly into the interior of the container around the acid bottle and its 100 supporting cage. A series of perforations 31 are formed near the upper contracted end of the baffle 30, for a part of its circumference, an imperforate portion being left on the side adjacent to the extinguisher outlet hereinafter referred to. Adjacent to the lower edge of the baffle 30 a second and smaller conical baffle 35 is rigidly secured by rivets 36. This baffle 35 is supported by its larger circumference and contracts and inclines inwardly toward the acid bottle, it being formed with a central opening which

freely surrounds the bottle and its supporting cage.

40 is a metal marker arm supported from the baffle and extending downwardly to a point up to which the soda solution should normally be filled in the container.

At one side of the tank 1, near its upper end, I provide an outlet elbow or goose neck 50, which extends upwardly to a point adjacent to the mouth of the extinguisher tank. Secured to the downwardly curved end of this elbow 50 is the usual flexible discharge pipe 51. A strainer 52 extends over the inner opening of the discharge elbow 50, and a curved baffle plate 55 is secured to the inner surface of the container, extending over the greater portion of the strainer 52 and closed entirely below and at the ends, so as to permit entrance of the liquid to the outlet only over the top of the baffle 55. This shell-like baffle 55 is securely fastened at its edge to the inner surface of the container 1.

In operation the container 1 is filled with the soda solution up to the indicator 40, and the acid bottle 20-21 is filled to the marker 22, in the central contracted neck 22. When it is desired to operate the extinguisher it is inverted to cause the acid to flow out of the bottle into the surrounding soda solution causing pressure which forces the solution out through the goose neck 50 and discharge pipe 51. The baffle 30, being imperforate adjacent to the outlet it will be understood that the escaping acid will be compelled to mix with the soda solution before it can reach the outlet, thereby preventing the escape of the acid directly to the outlet pipe.

When the device is upright it will be observed that since there is a small surface of acid in the bottle exposed in the contracted central neck 22, there will be minimum disturbance of the acid from the shaking of the extinguisher, whether in handling or from the vibration of the apparatus, upon which it may be mounted. Any accumulation of moisture from the soda solution into the acid bottle beneath the loose stopple will be amply taken care of by the upper chamber 45 of the double bottle. Any disturbance of the acid in the double bottle will only cause it to splash upwardly upon the walls of the upper chamber from which it will drain back down into the lower portion of the bottle, the second or open neck of the bottle 50 at the top being relatively so small that there is practically no danger of the acid being splashed out of the double bottle. Most splashing of the soda solution will be caught 55 by the peculiar form of baffle and returned to the body of the liquid, but if, by chance, some little bit of the solution should splash up into the space covered by the outlet baffle

55, it will be observed that this can not creep up through the outlet goose neck 50, since 65 it would overflow and run back into the main body of the liquid before it could get high enough into said goose neck.

I claim:

1. A fire extinguisher of the type described, comprising a tank or container having a suitable outlet, an acid bottle receptacle supported in the tank or container, and an acid bottle formed with a contracted neck between its ends dividing the bottle into two communicating chambers, and an open mouthed neck at one end in communication with one of said chambers.

2. In a fire extinguisher, the combination of an open mouth container for an extinguishing fluid, a closure for said mouth, an outlet in the form of a goose neck or elbow extending from the container body upwardly toward the plane of the mouth, a discharge pipe leading from said elbow, a baffle upon the inside of the container over the opening to the said discharge elbow, an acid bottle cage, a conical baffle surrounding said bottle cage, and an acid bottle mounted in said cage, as set forth.

3. In a fire extinguisher, the combination of a container having an open mouth, a closure for said mouth, an outlet from said container in the form of a goose neck or elbow extending from the container body upwardly toward the mouth, a discharge pipe leading from said elbow, a baffle upon the inside of the container over the opening in the said discharge elbow, an acid bottle support, a conical baffle supported at its small end in the mouth of the container and flaring therefrom outwardly and downwardly into the container, and an auxiliary baffle supported upon the main baffle upon its larger circumference and projecting inwardly and downwardly therefrom toward the bottle cage, and an acid bottle mounted in said cage, as set forth.

4. A fire extinguisher of the type described, comprising a tank or container having a suitable outlet, an acid bottle receptacle supported in the tank or container, an acid bottle formed with a contracted neck between its ends dividing the bottle into two communicating chambers, and an open mouthed neck at one end in communication with one of said chambers, a conical baffle supported at its small end in the mouth of the container and flaring therefrom outwardly and downwardly into the container, and an auxiliary baffle supported from the main baffle upon its larger circumference and projecting inwardly therefrom toward the bottle cage which it surrounds.

HARRY M. McCASLIN.
